UNITED STATES PATENT OFFICE.

CHARLES W. LINDSAY, OF HOUSTON, TEXAS.

SINGLE-TRIGGER MECHANISM FOR DOUBLE-BARREL FIREARMS.

Application filed July 18, 1927. Serial No. 206,583.

The following is a full and exact description of my invention which has for its object; viz,

1. To provide a single trigger mechanism of fewest parts possible, which is simple in operation, sure in action and stable in adjustment.
2. To provide a single trigger mechanism of this character whereby the two barrels may be fired in a fixed order of succession or, by means of a sear-lift-slide, one barrel alone may be fired repeatedly while the other barrel remains inactive.
3. To provide a single trigger mechanism of said character in which, after the initial barrel has been fired, the second barrel is effectively prevented from prematurely firing, incident to the rebound and involuntary trigger pull.
4. To provide a single trigger mechanism of said character, which is suspended by a pivot from the upper tang of the main frame and thereby is not influenced in its adjustment or operation by a defective stock, loose or maladjusted trigger plate.
5. To provide a single trigger mechanism of said character which is actuated by a hammer sear acting upon a pivoted movable lever.
6. To provide a single trigger mechanism of said character, actuated by a hammer sear and regulated in its selective sear setting operation by an opposing controller-spring.
7. To provide a single trigger mechanism of said character which is set for operation by a hammer sear, and also released from this position, through the respective cocking and releasing of the hammers.

These objects are attained by a mechanism composed of the following parts; viz, 1, a "carrier-bar," 2, a "sear-lift," 3, a "sear-lift-setter," 4, a "controller-spring" and 5, a "sear-lift-slide" with its 6, "holding-spring." These parts are hereinafter more fully described and are illustrated by the accompanying drawings in which—

Fig. 1 is a perspective view of the main frame with barrels and stock removed and showing, in dotted lines, the hammers in cocked position and the trigger mechanism in position to fire the right barrel. Fig. 2 is a perspective view of the two hammer sears with the trigger mechanism in the act of releasing the right sear. The left sear 55 is not disturbed as its rear end projection passes through a lateral notch in the sear-

lift as the latter is moved upward by the vertical plate of the trigger. Fig. 3 is a similar view to Fig. 2 after trigger has been released, showing the sear-lift moved to its most forward position with a shoulder underneath the left hammer sear preparatory to releasing the left hammer, and showing the right hammer sear in its lowest position and free of the sear-lift. Fig. 4 shows the sear-lift moved to its most rearward position by the action of the sear-lift-slide thus permitting only the left barrel to be fired, as the right hammer sear is again free of the sear-lift. Fig. 5 is a detailed view of the carrier-bar. Fig. 6 is a detailed view of the sear-lift. Fig. 7 is a detailed view of the sear-lift-setter. Fig. 8 is a detailed view of the controller-spring assembly. Fig. 9 is a side elevation of the sear-lift-slide.

Referring more specifically to the drawings wherein similar numerals refer to the same parts throughout the several views 1, designates the frame of the usual double barrel firearm which houses the firing mechanism. In the sides of frame 1, are pivoted the hammer holding sears 2, 2. At the posterior ends of the sears 2, 2, are lateral projections 3, 3, which point toward each other and are arranged to extend over and in the path of a sliding sear tripping lever 4, called the sear-lift and shown in Fig. 6.

In a groove on the under side of the upper tang 5, with a pivot 6, through its upper end, the carrier-bar 7, is suspended, so that it has considerable backward and forward motion which is necessary in the operation of the mechanism. The lower end of the carrier-bar 7, is pivoted by a pin 8, into the bifurcated posterior end 9, of the sear-lift 4. Near the middle of the carrier-bar 7, is pivoted by a pin 10, the sear-lift-setter 11, (Fig. 7). From the anterior edge of the carrier-bar 7, is a projection 12, which has its tip turned outward and over the path of the sear-lift-setter 11, so as to steady it and check excessive upward movement.

The sear-lift-setter 11, is flat and pivoted at 10, near its middle to the carrier-bar 7. At its posterior end there is a projection 13, bearing a vertical hole 13^a, through which the lower end of the controller-spring's axial pin 18, (Fig. 8) projects and operates in maintaining close working contact between the anterior end of the sear-lift-setter 11, and the right hammer sear at 110

3. This anterior end is sloping on both its upper and lower front corners so as to form a blunt point or nose 14, which, through the exertion of the controller-spring, is kept in contact with the lateral projection 3, of the right hammer sear 2. (It could be adjusted to the left hammer sear instead.)

The sear-lift 4, is slightly curved from front to rear and has a bifurcated posterior end 9, into which the lower end of the carrier-bar 7, is pivoted at 8. On one lateral edge is a notch or indent 15, and opposite on the other lateral edge is a projection or lug 16. Both edges are arranged to serve in a selective manner by engaging one at a time the lateral projections 3, 3, of the hammer sears 2, 2, as the sear-lift 4, is moved back and forth beneath the sear projections 3, 3, by the carrier-bar 7.

20 The spiral controller-spring 17, (Fig. 8) encircles and is attached at its upper end to an axial-pin 18. This pin is pivoted at its upper end 19, to the under side of the upper tang 5, posterior to the pivot 6, of the carrier-bar 7. The lower end of this axial-pin protrudes through the vertical hole 13^a in the projection 13, on the posterior end of the sear-lift-setter 11. This controller-spring assembly exerts a continuous force to 25 the front, tending to push forward the entire trigger mechanism and thereby maintaining close working contact between the sear-lift-setter 11, and the hammer sear projection 3. Also when pressure on the 30 trigger is completely released after firing the first hammer, the controller-spring pushes forward the carrier-bar 7, with its sear-lift 4, so that the second hammer sear 3, will be engaged by the sear-lift 4. At the 35 same time this frees the first sear, thereby shifting the action of the trigger 20, from the first to the second hammer sear, which in turn will be fired when the trigger is again pulled.

45 Mounted upon and extending through the trigger plate 21, is the sear-lift-slide 22, (Fig. 9) provided on the under side of the trigger plate 21, with a shifting thumb piece 23. As the sear-lift-slide 22, is moved 50 backward by the thumb piece 23, it causes a vertical post 24, to impinge against a detent 25, on the sear-lift 4, thereby compressing the controller-spring 17, and moving the entire mechanism backward 55 so far that the lug 16, on the sear-lift 4, is placed behind the right sear projection 3, thus leaving the right hammer sear free of the sear-lift 4. The projection 3, on the 60 opposite or left hammer sear will now continuously engage the shoulder of the sear-lift 4, in front of the indent 15, thus permitting the left barrel only to be fired repeatedly. As the thumb piece 23, is now moved forward the vertical post 24, will 65 impinge against the lug 16, of the sear-lift

4, thus moving the entire mechanism back to its original position. The vertical bar 26, is an integral part of the sear-lift-slide 22, and contains a curved slot 27, into which projects one end of a holding-spring 28, that serves to hold the slide in either of its two possible positions.

The operation of the mechanism is substantially as follows. Whenever the hammers are cocked, by whatever means according to the make of firearm, the anterior ends of the hammer sears 2, 2, are pushed downward by the hammers, thereby elevating the posterior ends 3, 3, of the sears. As the posterior end of the right, or chosen sear 75 comes up it impinges against the under sloping surface of the anterior end of the sear-lift-setter 11, forcing it backward until only the nose or point 14, makes contact with this hammer sear. As the sear-lift-setter is thus being forced backward by the hammer sear 3, it carries backward with it the whole mechanism including the carrier-bar 7, and also compresses the controller-spring 17. As the carrier-bar is thus forced 80 backward it pulls with it the sear-lift 4, and the latter is brought into such a position in relation to the projections 3, 3, on the posterior ends of the hammer sears, that the lug 16, is underneath the right sear and the indent 15, is underneath the left sear, this being the relative position of the parts when the hammers are in cocked position as 85 shown in Fig. 1.

Upon pulling the trigger, its vertical 100 blade that extends upward through a slot in the trigger plate 21, will impinge against the under side of the sear-lift 4, thereby raising it, which in turn by means of its lug 16, will raise the rear end 3, of the right hammer sear until it releases that hammer. Since the projection 3, on the left hammer sear is over the indent 15, in the sear-lift 4, the left hammer sear is not affected by this 105 movement. When the rear end of the right sear was being raised its lateral projection 3, moved over the nose or tip 14, to the upper sloping surface of the anterior end of the sear-lift-setter 11. This is the position 110 of parts when right barrel is fired as shown by Fig. 2.

By releasing the trigger, its vertical blade, the sear-lift 4, and right sear 3, will all 115 descend to a position of rest. In its descent the lateral projection 3, of the right (or chosen) sear will pass from the upper sloping surface over the nose or tip 14, to the under sloping surface of the anterior end of the sear-lift-setter 11, thus allowing the 120 whole trigger mechanism to be pushed forward by the compressed controller-spring 17. As the carrier-bar 7, goes forward it pushes the sear-lift 4, forward until the shoulder just behind the indent 15, engages 125 the lateral projection 3, on the rear end of 130

left sear, and the lug 16, passes in front of the lateral projection 3, on the rear end of right sear, leaving the right sear free. The parts are now in position to fire the second or left barrel as shown by Fig. 3.

When the trigger is again pulled the sear-lift 4, is raised as before but on account of its new position, the left sear only is now raised until it releases the left hammer. 10 Since the right sear is free of the lug 16, it is not affected by this movement. This is the position of parts when left or second barrel is fired.

By again releasing the trigger, its vertical blade, sear-lift 4, and left sear 3, will descend to a position of rest, thus completing the cycle of movements incident to cocking and firing both hammers in a fixed order of succession.

20 If it is desired to fire the left barrel only or repeatedly, the sear-lift-slide 22, is pulled backward by the thumb piece 23, which will pull the entire trigger mechanism backward until the right hammer sear no longer makes contact with the sear-lift 4, and thus remains inactive. But the left hammer sear makes continuous contact with a shoulder of the sear-lift 4, just in front of the indent 15, and is raised to release the left cocked hammer each time the trigger is pulled, as shown in Fig. 4.

When the right or first barrel is fired the sear-lift-setter 11, is held firmly between the rear end 3, of right sear and the projection 12, on carrier-bar 7, so that it is unable through the force of the controller-spring 17, to push the sear-lift 4, forward into position to release the left or second hammer. During the recoil the carrier-bar 40 7, and its attached parts 4 and 11, are held in this fixed position, first by the pull on the trigger and second by the "inertia of rest" of these parts. As the recoil ends and the rebound begins the carrier-bar 7, and 45 its attached parts 4 and 11, are pulled backward by the "inertia of motion" which these parts attained during the recoil, and which is great enough to overcome the constant forward acting force of the controller-spring 17, thereby again preventing the sear-lift-setter 11, from getting the sear-lift 4, in position to release the second hammer. During this rebound as the trigger forcibly makes contact with the finger so as to cause 55 an involuntary trigger pull, the right hammer sear 3, will again be raised as during the original voluntary trigger pull, since up to this time the sear-lift-setter 11, has not succeeded in getting the sear-lift 4, moved from

the first to the second hammer sear. But the instant the rebound has been stopped the sear-lift-setter 11, through the controller-spring 17, as hereinbefore described, pushes the sear-lift 4, forward. This movement releases the right sear and engages the left 65 sear, which is now in position to be released by the next voluntary pull on the trigger, be that as soon as one chooses after making the first trigger pull, and yet the premature firing of the second barrel has been effectively avoided.

It is to be understood that various changes may be employed and modifications of structure made, such as changing the order of firing, or selection of hammer sear 75 to actuate the trigger mechanism, without departing from the spirit of the invention.

What I claim and wish to secure by Letters Patent is:—

1. A single trigger mechanism for double barrel firearms, in combination with hammer sears and a common sear actuating means, a carrier-bar suspended on a pivot from the tang of the main frame and carrying a sear-lift and sear-lift-setter back and forth in 85 their selective action upon the hammer sears.

2. A single trigger mechanism for double barrel firearms, in combination with hammer sears a common sear actuating means and a carrier-bar, a controller spring spiraled 90 around an axial pin that is pivoted at its upper end to the upper tang, behind the carrier bar, and connected at its lower end to the sear-lift-setter thereby maintaining close working contact between the mechanism and the hammer sears, substantially 95 as described.

3. A single trigger mechanism for double barrel firearms, in combination with hammer sears and a common sear actuating means, 100 a sear-lift-setter consisting of a projection extending anteriorly from the carrier-bar and having a sloping under surface whereby the rise and fall of the posterior end of the selected actuating hammer sear against the 105 said sloping surface will govern the position of the carrier bar and its assembly, substantially as described.

4. A single trigger mechanism for double barrel firearms, in combination with hammer sears and a common sear actuating means, a carrier-bar and controller-spring each pivoted in the top tang and mutually adjusted in weight and tension whereby premature firing of the second barrel is 115 avoided, substantially as described.

CHARLES W. LINDSAY.
